[57] CLAIM

The ornamental design for a pet pouch, as shown and described.

DESCRIPTION

FIG. 1 is a top and side perspective view of my new design for a pet pouch;

FIG. 2 is a reduced perspective view thereof, the broken lines are for purposes of illustration only and form no part of the claimed design;

FIG. 3 is a rear elevation view thereof;

FIG. 4 is a front elevation view thereof;

FIG. 5 is a top plan view thereof; and,

FIG. 6 is a side elevational view thereof, the opposite side is identical.
